WATER SOFTENING APPARATUS

Samuel Smith, Toronto, Ontario, Canada

Application August 19, 1936, Serial No. 96,767
Renewed June 7, 1939

4 Claims. (Cl. 210—24)

This invention relates to water softening apparatus and applies more particularly to that type of apparatus utilized in the art of water softeners.

Among others, one of the objects of the present invention is to provide a device of this character wherein air is introduced into the water prior to the water being introduced to the apparatus.

Another object of the present invention is to provide an apparatus of this character wherein the structure is not required to be dismantled for "flushing-out" or revivifying purposes.

A further object of the invention is to provide a device of this character with which water when introduced in a finely divided or atomized state, is cleansed of foreign solids prior to the removal of the hardening constituents.

A still further object of the present invention is to provide a device of this character in which the casing or tank is subdivided into a plurality of compartments defined by foraminous structure in the form of suitable mesh screens.

Yet a further object of the invention is to provide a device of this character composed of few parts and simple structure which will the more efficiently perform the functions required of it.

Having regard to the foregoing and other objects and advantages which will become apparent as the description proceeds, the invention consists in the novel combination and arrangement of parts hereinafter described in full detail and illustrated in the accompanying drawing in which,

Fig. 1 is a longitudinal, vertical section taken through the center of an embodiment of my invention.

Fig. 2 is an enlarged sectional elevation of the conoidal member associated with the service outlet.

Fig. 3 is an enlarged sectional detail illustrating the means for introducing air into the hard water.

Referring now to the structural details of my invention in which like letters and numerals of reference designate corresponding parts, the letter A indicates a casing or tank of suitable proportions formed with head and base B and C respectively. The head and base members may be welded to the casing or, as indicated at 10 and 11 may be threadedly connected and provided with a washer 12 to effect a water tight joint.

Internally, the tank or casing is provided with a plurality of screen members 14 of suitable mesh which subdivides or virtually defines a series of separate compartments 15. Immediate support for the screen members is provided in the form

of projections, rings or like devices 16, it will be observed however that the "fill" in each zone or compartment forms a support for the next succeeding compartment with the lower-most screen preferably convex.

Each of the compartments or zones 15 are filled with comparatively small pieces of baked fire clay 17 which are relatively uniform in size. This baked clay possesses the necessary properties for removing the hardening constituents such as sulphates, carbonates, alkaline metals, etc., from the hard water.

Immediately above the uppermost compartment 15 is a division or compartment 18. This latter is preferably filled with sand or suitable filtering materials 19 for the filtration or cleansing of the water passing therethrough. Directly above the compartment 18 and "fill" 19 is an unfilled section which forms an atomizing chamber 20.

Mounted centrally in the head B is the pipe or conduit 21. This conduit communicates with a source of water to be softened and is provided with a shut-off valve 22, a controlled air inlet 23 and a spray or atomizer 24. The atomizer 25 it will be observed is within the chamber 20 removed from the fill 19, thus water entering the casing is finely divided and broken up to substantially vapour form before settling upon the filtering or cleansing material.

The means for introducing air directly into the water prior to entrance to the apparatus comprises a Y branch fitting 25 provided with a hinged flap valve 26 normally held in a closed position by means of a spring 27 and a shut-off valve 28 which enables the air to be shut off entirely. During operation of the apparatus or when it is deemed advisable or necessary, the valve 28 is opened. As the incoming water passes through the pipe 21 a vacuum is created which automatically opens the flap valve 26 and causes air to be drawn into and commingled with the water and in such form passes to the spray. The vapourizing or spraying of the water with the previously introduced air accelerates the escape of carbon dioxide or hydrogen sulphide and at the same time the absorption of oxygen aids in the precipitation of iron from solution.

At the base of the apparatus I arrange a conduit or service outlet 29 which is provided with a suitable shut-off valve 30. Within the apparatus and mounted upon the upper extremity of the conduit 29 is a conoidal member 31 (see Fig. 2). This member may take the form of a casting or be composed of a series of superimposed rings 32

so formed as to provide a multiplicity of narrow slits 32 through which the softened water passes on its way to the outlet 29. Internally of the conoidal member I provide a screen 33 while the head, it will be observed, is detachably mounted for screen removal or cleaning.

As it will be found desirable or necessary to flush-out the apparatus or revivify the materials therein, I provide suitable means in the form of 10 a valve controlled inlet 34 and a valve controlled outlet 35. The inlet 34 may of course be employed as an auxiliary outlet should additional or extra water service be required.

From the foregoing it will be seen that I have 15 developed an extremely simple and practical apparatus for the softening of hard water and at the same time one that may readily be cleansed or "flushed out", and the acting material as occasion or circumstance dictates, revivified.

Changes may be made in the above structure 20 and many apparently widely different embodiments constructed without departing from the spirit or scope thereof. It is intended therefore that all matter contained herein shall be interpreted as illustrative rather than in a limitative sense.

What I claim as my invention is:

1. In a device of the character described, an 25 upright casing, water softening material in the middle of the casing and spaced from the top and the bottom of the casing, a water outlet pipe leading from the lower part of the casing below the water softening material, a water inlet pipe connected with the upper part of said casing above the water softening material, spray means 30 on said water inlet pipe within the casing to substantially atomize water introduced into the upper part of the casing, and an air inlet connection to said water inlet pipe in advance of the spray means to take in air to flow with the water through the spray means.

2. In a water cleaning and softening apparatus, an upright casing, a screen in the upper part 40 of said casing spaced from the top thereof, a second screen in the lower part of said casing and spaced from the bottom thereof, water softening material in said casing between the

5 screens, a water inlet pipe leading to the top of the casing, spray means on the discharge end of said water inlet pipe within the casing to substantially atomize water introduced to the casing above the upper screen, an air supply connection to the water inlet pipe in advance of the spray means, and an outlet pipe leading from said casing below the lower screen.

3. In a device of the character described, an 10 elongated upright casing, a plurality of screens mounted across within said casing to define a plurality of compartments with an inlet compartment in the upper part of the casing and a discharge compartment in the lower part of the casing, water cleaning and softening material 15 in the compartments in the middle portion of the casing, a water inlet pipe connected in the upper part of the casing, a water discharge outlet pipe connected in the lower part of the casing, spray means within the casing on the discharge end of the water inlet pipe, a branch air inlet pipe connected with the water inlet pipe, and valve means in said air inlet pipe through which air is introduced with the water by aspiration.

4. A water cleaning and softening apparatus 20 comprising, an elongated casing tank disposed in upright relation and provided with a domed top, a plurality of screens mounted in said tank in substantially horizontal planes spaced below the domed up top and above the bottom of the 25 tank to thus define compartments, water cleaning material in one of said compartments, water softening material in another of said compartments, a water inlet pipe connected through the domed top of the tank, a water discharge pipe 30 connected through the lower part of the tank, a spray head within said tank on the discharge end of the inlet pipe to substantially atomize water introduced therethrough, an air inlet pipe connected with said water inlet pipe in advance 35 of the spray head, valve means in said air inlet pipe opened by flow of the water to allow commingling of air with the water, and valve means to control said water inlet and outlet pipes and said air inlet pipe.
